HAIRDRESSING APPLIANCE

Stanley R. Chester, Toronto, Ontario, Canada

Application September 7, 1954, Serial No. 454,499

7 Claims. (Cl. 132—7)

This invention relates to apparatus for reworking hair in order to cause the latter to curl.

In more recent times it has been observed that hair which normally grows and arranges itself in substantially straight strands, can be made to curl by changing the cross-sectional configuration of the hair strand.

Straight hair is almost invariably of circular cross section and many of the processes used to provide so-called "permanent waves" rely upon some means of distorting the cylindrical form of the strand to make it of oval shape so that the stresses within the strand become uneven thereby causing the strand to bend or curl.

Most of the hair curling processes of the prior art rely upon heat and pressure or upon one or other or both of these forces combined with chemical agencies to distort the hair into the desired cross sectional shape.

A marked disadvantage which characterizes all of these processes resides in the fact that the hair gradually restores itself to the original cylindrical shape and becomes straight again after an interval of time, the duration of interval usually depending upon the degree of violence of the forces which were applied to stress the hair beyond its normally stress-relieved condition.

A point to remember is that the hair which curls under these artificially applied stresses is initially unevenly stressed internally even when it curls in an effort to relieve the condition.

Hair strands, like any other mundane phenomenon tend to achieve stress-relief by internal agitation and regrouping of molecules within a surface envelope so as to achieve stress relief. This is sometimes referred to in mechanics as "aging."

It is an object of the present invention to provide apparatus and method whereby a hair strand can be distorted in shape permanently without stressing the hair strand internally, that is to say, without causing an increase of local stress at one point in the hair section which was not there when the hair was generated by nature. "Naturally curly" hair is known to be fully stress relieved internally, the curl being part of the means whereby the strand relieves uneven stresses.

I have discovered that it is possible to distort the stress pattern in a normally stress-relieved cylindrical hair strand by discretely removing a portion of this substance from one side of the strand. A hair strand so treated immediately restores itself to a stress-relieved condition by bending into an arcuate form resembling a curl. Since no stress has been added to the hair structure by my method, there is no interval of "shake-down" of the internal stress—it is immediately fully relieved as soon as the hair curls. Such a curl is therefore rigorously permanent.

The hair substance is removed from one side discretely, that is, in small successive amounts graded over the length of the strand which it is desired should curl.

This discrete removal of hair substance also constitutes a discrete method since the step-by-step removal of

2

hair substance particles is gentle and does not shock the hair structure as would be the case if the whole amount of material necessary to form a desired curl were removed in one stroke of a cutting tool. A method of curling wherein the whole cut on a curl is made in one stroke will apply added stress to the hair structure. The hair by this method will be confronted with two stresses, both of which cause the hair to curl. When internal agitation of the hair substance relieves one of these stresses the curl in the hair will change and become less so that the predetermined set of a hair curl arrangement is undesirably altered a short time after it has been effected. My method avoids this contingency thereby providing a hair curl arrangement which is rigorously permanent.

A preferred mode of carrying into effect the principles of my teachings, comprises a tool, having an edge portion, desirably serrated and coated with a finely-abrasive substance such as fine diamond dust. The hair strand is stroked gently on one side by means of this tool and a curved portion is removed discretely thereby so that the hair bends or curls in a direction concave toward the cut side. The degree of curl can be determined by the number of strokes used and to some extent by the pressure exerted by the tool against the side of the hair strand.

The invention will now be further elucidated by the following description of a preferred embodiment of apparatus and associated method in accordance with my teachings. The text should be studied in conjunction with the accompanying drawings wherein:

Figure 1 depicts a magnified view of a hair strand which has been processed according to my teachings.

Figures 2 and 2A depict a simple tool attached to a conventional comb for both combing and preparing the hair for grinding and for also grinding the hair surface.

Figure 3 depicts a more complicated tool which by its shape facilitates the hair grinding operation.

Figure 3A is a section on line 3A—3A of Figure 3.

Figure 4 depicts a simple motor driven grinding tool for use in processing hair according to my teachings.

Figure 5 is an illustrative sketch showing one phase of a method in accordance with my teachings.

Referring now to these drawings, Figure 1 depicts a hair strand in four conditions, A depicts the hair as a straight cylinder, B shows the hair A in an advanced stage of grinding whereby it assumes in part a concave shape, C shows the hair strand relaxed into an arcuate shape resembling a "curl," and D shows a strand of hair locally ground away at opposite sides to produce a curled form.

It will be evident that by cutting the hair on the other side it would curl the opposite way, and in order to provide "curly" effects in a long strand it may be expedient to cut both sides of the strand as at D, Fig. 1, so as to approximate an oval cross section. Such a cross section will not only become concave but will twist slightly thereby providing a very satisfactory curl.

The depth of cut, and the decision to grind the hair on one or two sides of the strand depends largely upon the condition, texture and fineness of the hair.

Those skilled in the art are aware that there is a very wide difference in samples of hair. Fine hairs may require only light grinding on one side whereas heavy "coarse" or "stubborn" hair may require extensive single or multiple grinds upon the surface in order to establish the desired shape distortions.

Of course, the foregoing discussion, referring only to one strand of hair has been purely philosophical and explanatory. In practice it is desirable to process a large number of strands simultaneously. To this end

I have devised certain tools for the purpose and these will now be described.

Figures 2 and 2A depict a tool comprising a conventional comb 1 having teeth 6 and a handle 3. The back of the comb is shown as modified to include a succession of shallow slots 2 having rounded bottom faces 4. The faces 4 of slots 2 and if desired the smooth back 5 of the handle are coated with an abrasive substance.

Any commonly known abrasive can be used such as corundum, silica dust or the like and this can be caused by known means to adhere firmly to the surfaces 4, 5 and present projecting cutting edges. It is however important that the materials comprising this abrasive surface should be very finely divided and have very sharp cutting surfaces which do not dull quickly during use.

In a preferred embodiment the abrasive surface should be comprised of fine diamond dust for the following reason. It has been pointed out that the hair should be ground off gently and discretely. Since the tool will be used over a long period of time and in the course of a single treatment will make many many strokes, the cutting material should be one of the highest possible reliability; a poor cutting tool having dull teeth does a poor job of grinding, and if dull enough may even tend to iron rather than grind the hair thus introducing an undesired form of temporary secondary stress in the hair strand.

The combination of a comb and hair grinder in one tool is a convenient expedient. The comb is used to sort out the strands into appropriate groups and the tool is simply tipped over against the strands at the desired points where a cut is to be made. The comb may be regarded as a guide for the tool and therefore a useful part of it.

When it is desired to grind in a localized manner the tool can be turned in the hand, the comb portion becoming the handle and the abrasive back 5 becomes a useful finishing or warding tool.

Figure 3 depicts a fork shaped tool 7. In a preferred arrangement the inner surface 8 of one fork tine 9 is coated with the abrasive and the edges of the tine are rounded, both tines 9, 10 presenting smooth contours except for the abrasive portion. In a further desirable modification the surface 8 is transversely corrugated; the troughs and ridges tend to resolve the hair strands into small groups. These groups tend to twist spirally as the tool is drawn over a hank of hair and so the successive strokes of the abrasive grind the hair at points which advance spirally. Such a phenomenon results in a very attractive form of curl when the tool is manipulated by one skilled in the art.

This tool can be twisted slightly when drawn over the hair. The handle 11 may desirably be knurled to ensure a good grip and control by the operator: by twisting the handle while drawing this tool over the hair strands the fork acts as a lock and holds the strands taut while the abrasive surface 8 does its work.

A useful modification of Figure 3 would place the abrasive on tine 10 instead of on tine 8. Using the handle twisting technique with such a tool modification would evolve a differently shaped curl.

In rare cases where thick stubborn hair strands are being processed it will be desirable to provide a tool similar to Figure 3 in which both tines are abrasive. However, such a tool must be used with discretion for the reason that a two edged attack on the hair strands can cause hair strand breakage. Such a tool would be useful nevertheless for a combined "thinning" and curling operation.

Figure 4 depicts a motorized grinding tool. This may be of conventional mechanical design having a grinding tool 13 rotated at high speed by a motor 12. The grinding surface 13 of such a tool should be of very fine texture, and should be stroked lightly upon the surface of the hank.

A preferred form of tool has the same outward appearance as Figure 4 but operates in a different manner. In the preferred embodiment the grinding head 13 is made to reciprocate axially as shown by the arrows between positions 14 and 15 and also revolves as per arrow 16. The rotation is preferably clockwise at 16 for "right handed" operators and counter clockwise for left hand use.

If the tool 13 rotates slowly and "see-saws" fairly rapidly—say 30 times per second, it is very effective as a grinder and involves a very small risk of catching, tangling and/or breaking hair strands. The tool is very conveniently operated by air motor but may also be electrically motorized. In a highly desirable modification the motor 12 may be of the vacuum type. An aperture 17 may vent the high pressure side of the motor, the inrush of air thereby drawing the grinding swarf off the work and disposing of its through the vacuum line 18. Hair grinding residues being very fine in mesh they will not injure the mechanism of the vacuum motor by passing through it. Such a tool is unique to the purpose herein presented.

It will be understood by those skilled in the art that very wide variations in grinding techniques will be required in pursuit of hair styling and in dealing with hair strands of widely varying texture and dimension.

Figure 5 has been included for the purpose of orienting the skilled mind in the direction of my new techniques and teachings. The illustration in Figure 5 may be regarded as being especially applicable to what the hair stylist regards as a difficult case—that of coarse hair.

According to the method of my teachings a hank of hair 19 is pulled down taut by known means at the ends 20, and may be combed out by a tool such as that of Figure 2A and by moving the abrasive surface up and down against the hairs in a zig-zag motion as shown. The treatment is repeated many times for each of the first, second and third waves, applying the abrasive tool to both sides of the hair hank.

Skilled artists will make use of the fingers to press against the hank, increasing and decreasing the pressure artfully to make a desired styling of curl.

Of course, any number of curls may be made and it will be evident to one skilled in the art that now the technique can be varied to provide loose and tight and twisty curls as desired.

Figure 5 shows only the treatment of one lock or hank of hair. Other portions of the subject's hair may be successively treated in a similar manner.

For fine textured hair, the tools may be pulled through a lock or hank of hair or may simply be pressed against appropriate areas of the hair as it lies upon the head and drawn, usually in some sort of zig-zag fashion, along over the head contour pressing down where a curl is wanted and releasing pressure where no curl is desired or where the phase of a curl is to be turned or reversed.

It is to be understood that the foregoing description and illustration of my teachings is strictly exemplary and not limiting.

In the profession of hair styling there is room for almost infinite variation of the techniques of manipulation of the abrasive tools and many tools of odd configuration may be found advantageous in the course of pursuing a fancied hair style. All such, however, when they follow my teachings in regard to the discrete removal of a portion from the side of a hair strand will lie within the broad spirit of my invention and are to be regarded as lying within the ambit of the appended claims.

What is claimed is:

1. The method of curling hair which comprises grinding away a side portion of the hair strand in discrete successive steps in such a manner as to evolve an area of unbalanced stress within the hair structure.
2. The method of curling hair which comprises selecting specified hank thereof and combing it into a flat sheet,

dividing the sheet into parallel rows of strand groups and grinding out a contour on one side of each said strand group.

3. The method of curling hair which comprises selecting a specified hank thereof, combing it into a flat sheet, dividing the sheet into a series of strand groups all held in substantially parallel relation by means of a slotted tool wherein each strand group is restrained within the walls of a slot, and then by means of an abrasive face characterising the bottom of each slot, grinding off a portion of hair by sliding the tool back and forth along the hair strands, exerting the abrasive action against the hairs in discrete successive waves of force.

4. The method of curling hair which comprises selecting a specified hank thereof, combing it into a flat sheet, dividing the sheet into a series of strand groups all held in substantially parallel relation by means of a slotted tool wherein each strand group is restrained within the walls of a slot, and by applying abrasive means characterising the bottom face of each restraining slot, grinding off a portion of hair by sliding the tool back and forth along the hair strands in a zig-zag motion and exerting the abrasive action against the hairs in discrete waves of force whose frequency is timed to synchronize with the said zig-zag motion so as to cause the abrasions in the hair strands to define a spiral pattern upon each strand group.

5. A hair processing tool for the purpose stated comprising a rigid member characterized by a series of slots

cut into one side thereof, each slot having two juxtaposed smooth side walls and a bottom face coated with abrasive material, and a handle associated with said rigid member.

5 6. A hair processing tool for the purpose stated comprising a rigid fork shaped member having a handle and two tines, an undulating abrasive surface characterizing the inner surface of one tine, and a smooth substantially non-abrasive surface characterizing the juxtaposed inner surface of the other tine.

10 7. A hair processing tool for the purpose stated comprising a rigid member characterized by a series of substantially rectangular slots cut transversally along one side thereof, each slot having smooth substantially non-abrasive side walls and a highly abrasive bottom face, comb-like means radiating transversally from another side of said rigid member and a handle for gripping and manipulating the tool.
